UNITED STATES PATENT OFFICE

1,953,812

ELECTRICAL CUT-OUT

George F. Lincks and Francis L. Flanagan, Pittsfield, Mass., assignors to General Electric Company, a corporation of New York

Application May 5, 1932, Serial No. 609,467

6 Claims. (Cl. 200—50)

The invention relates to electrical cutouts, and more particularly to groups of oil cutouts used to protect the several phases of an electrical circuit.

If it becomes necessary to make repairs on the circuit or apparatus protected by an oil cutout, it is common practice to open the circuit by removing the fuse carrier from each of the cutouts, or by turning the several fuse carriers to a position where the terminals thereof no longer engage or make contact with the respective circuit terminals. Heretofore, such a method of interruption necessitated the breaking of the circuit by steps, that is by opening one leg or phase at a time, as each cutout was installed as a separate individual unit, having no connection whatsoever with the other cutouts. Opening the circuit in such a manner may cause an unbalancing of the load or throw an overload on the conductors still in closed circuit, which may cause either a blowing of the fuses in the closed cutouts or cause a large arc to be drawn when they are opened.

The object of the invention is the provision of means for interlocking the fuse carriers of a series of cutouts in the several phases of a circuit in such a manner that the opening of one phase of the circuit by rotating or moving the fuse carrier in any one cutout will similarly and simultaneously rotate or move the fuse carrier of each of the other cutouts.

A better understanding of the invention may be had by explaining it in conjunction with the accompanying drawings which illustrate one embodiment thereof and in which Fig. 1 is an elevation showing the invention as applied to two subway cutouts, one of which is shown partly in section; Fig. 2 is a top plan view thereof; Fig. 3 is a fragmentary section taken through 3—3 of Fig. 2 and showing the safety latch; Fig. 4 is an elevation of a three phase cutout partly in section; Fig. 5 is a top plan view and Fig. 6 is an end view.

Referring to Figs. 1 and 2, the casing 1 of the cutout shown consists of a lower cup-shaped member or tank 2, threaded into the cored-out top part 3, which is provided with two oppositely disposed and downwardly projecting bosses 4, a centrally disposed top aperture 5, and a hanger 6 by which the cutout may be attached to a wall or other support.

The lead sheath coverings of the cables are connected to the sleeves 8 by a wiped joint, or other means, and the conductors of the cables 55 are connected to leads 11 which enter the cut-

outs through the apertures in the bosses 4, as shown in Fig. 1, a fluid-tight joint being formed by the glands 9 and sealing compound 10. The leads 11 are connected respectively to oppositely disposed contacts or circuit terminals 12 which are fastened insulatively to the casing 1. The circuit is completed through the cutouts by means of a fuse 13 connected to the contacts or terminals 14, mounted on rotatable and removable carriers 15 and adapted to engage the circuit terminals 12 when the carriers are inserted into the casings 1 through apertures 5 and turned to the position shown.

The fuse carriers 15 comprise metallic head caps or covers 16 and projecting members 17 mounted therein, the latter being of insulating material such as oil treated wood, molded compound or the like. The caps 16 are provided with descending flanges 18 which fit about the annular and upwardly projecting flanges 19 of the casing top parts 3. They are also provided with two oppositely-disposed bayonet lugs 20, which slide downwardly through slots 21, cut from or formed in the side wall 22 of the central apertures 5, until they clear the side walls 22, whereupon the carrier is rotated until the faces of contacts 14 are in full electrical engagement with the faces of contacts 12, the lugs 20 cooperating with the lower edge of the annular walls forming the apertures 5 to lock the carriers in the cutouts.

Removal of the carriers 15 from the casings 1 requires that they be turned with respect to the casings until the lugs 20 register with the slots 21. This rotation moves the contacts 14 around and out of contact with the contacts 12, thus breaking the electrical circuit through the cutouts. As the contacts 12 and 14 are submerged in oil, it is evident that if the carriers in the group of cutouts can be simultaneously operated, they may be used as an effective and safe polyphase switch for opening or closing the circuit.

When the fuse carriers 15 are in the casings, they are further clamped tightly in position by the set screws 24 in the yokes 23 which are pivotally mounted in the lugs 25 on the top part of the casing.

According to the invention, a pinion gear, or as illustrated, a segment of a pinion gear 26, is secured to the cap 16 of each fuse carrier 15 as by bolts, the periphery of the gear being disposed concentrically with relation to the axis of rotation of the carrier to which it is attached. The teeth of the pinions 26 mesh with the teeth of 110

a rack gear 27 held slidably in position by guides 28 bolted to the ends of the several hangers 6. The guides 28 are provided with aligned slots into which the rack freely fits, it being held in place by plates 29 bolted to the tops of the guides.

By so interconnecting the separate fuse carriers, the turning of one fuse carrier 15 or the moving of the rack 27 simultaneously turns all of the other fuse carriers, and thus simultaneously 10 opens or closes the several phases of the circuit protected by the group of cutouts.

As a further protection, safety latches or locking devices 30 are provided, and so arranged, as shown in Fig. 2, that removal of any yoke 23 is prevented when the cutouts are in closed circuit position or movement of the rack to close the cutouts is prevented if one of the yokes is not in its proper or normal position.

The safety locking devices comprise latches 31 20 mounted in guides 32, fastened to one of each pair of lugs 25, the latches being biased away from the rack gear 27 by springs 33 abutting against annular heads 34 mounted on the rear ends 35 of the latches.

The latches 31 are of such length that they bridge the space between the lower cam-shaped ends of the yokes 23 and the rack gear 27, and thus whenever all of the fuse carriers are in closed position, and the teeth of the rack 27 30 are not adjacent to the ends of the latches 31, the yokes 23 are held in position over the fuse carriers, but when all the fuse carriers are in open position the teeth spaces on the rack gear are then in positions adjacent to the ends of the latches which permits any one or all of the yokes 35 to be pulled forward, the cam-shaped ends 36 of the yokes forcing the latches into the spaces between the rack teeth which prevents any movement of the rack 27 and the turning of the unremoved fuse carriers 15 to closed circuit position.

Referring to Figs. 4, 5 and 6, in which is illustrated an arrangement of three cutouts for a three phase circuit with a single casting 37 serving as a cover for the three cutouts. Obviously this cover might also consist of three separate castings or parts bolted, welded or similarly fastened together to form the single casting 37. The three tanks 38, 39 and 40 are all threaded 50 into the casting or cover 37. With this arrangement the pinions 26' and rack 27' can be enclosed within the casing. This eliminates the difficulties experienced with exposure of the pinions and rack to atmospheric conditions. The formation of ice on the pinions and rack is especially undesirable because it may cause them to stick. The pinions 26' are secured adjacent 55 openings 41 in the cover 37 through which the fuse carriers 15 are inserted by means of clamping rings 42 which are secured to annular projections 43 on the cover 37 by screws 44. Pinions 26' are provided with slots 45 engaging the bayonet lugs 20 to rotate the fuse carrier 15 when the rack 27' is oscillated. The fuse carriers 15 60 and the cooperating contacts and supports are the same as shown and described in connection with Figs. 1 and 2. Barriers 46 are provided be-

tween adjacent cutouts. Each cutout is provided with a separate vent 47. Each cutout is provided with a wiping sleeve 8' for making connections to a lead sheathed cable on one side and a flexible cable 48 on the other side. Obviously, 80 conditions would determine whether lead sheathed, flexible, or other cables would be used.

What we claim as new and desire to secure by Letters Patent of the United States, is:

1. A set of electric cutouts, each provided with a removable and rotatable fuse carrier, a pinion mounted on each carrier, a rack for simultaneously actuating said pinions, and means for automatically locking said rack in extreme position upon removal of a fuse carrier. 85

2. An electric cutout for multi-phase circuits comprising a housing, a plurality of fuse carriers located in said housing, means to move one fuse carrier to close a circuit through one phase, means for simultaneously moving the other fuse carriers to complete the circuit through the corresponding phases including a pinion connected to each fuse carrier and a rack engaging said pinions, and means to prevent the movement of one fuse carrier to close the circuit when one 100 of the fuse carriers has been removed. 90

3. In combination, a plurality of cut-outs adapted to be connected in an electrical circuit, a fuse carrier for each cut-out, means interconnecting said fuse carriers whereby movement of one causes simultaneous movement of the other, and means to prevent the movement of one fuse carrier when another fuse carrier is removed from the cut-out. 105

4. In combination, a plurality of cut-outs 110 adapted to be connected in an electric circuit, a rotatable fuse carrier provided for each cut-out, means interconnecting said fuse carriers to cause simultaneous movement, means to prevent the movement of one fuse carrier when another fuse 115 carrier has been removed from the cut-out, and means to prevent the removal of a fuse carrier from its cut-out when it is connected in the electric circuit.

5. In combination, a plurality of cut-outs 120 adapted to be connected in an electric circuit, a rotatable fuse carrier provided for each cut-out, a pinion connected to each fuse carrier, a rack engaging each pinion to move the fuse carriers simultaneously, and a safety lock adapted to 125 engage the rack and prevent movement of the fuse carriers when one fuse carrier has been removed from its cut-out.

6. In combination, a plurality of cut-outs 130 adapted to be connected in an electric circuit, a rotatable fuse carrier provided for each cut-out, a pinion connected to each fuse carrier, a rack engaging each pinion to move the fuse carriers simultaneously, and a safety lock adapted to engage the rack and to prevent movement of the 135 fuse carriers when one fuse carrier has been removed from its cut-out and to prevent the removal of a fuse carrier from the cut-out when it is connected in the electric circuit. 140
